UNITED STATES PATENT OFFICE.

BENJAMIN G. BUTLER, OF COLUMBIA, SOUTH CAROLINA.

ICE-CREAM FREEZER.

No. 878,709.

Specification of Letters Patent.

Patented Feb. 11, 1908.

Application filed March 28, 1907. Serial No. 364,991.

To all whom it may concern:

Be it known that I, BENJAMIN G. BUTLER, citizen of the United States, residing at Columbia, in the county of Richland and State of South Carolina, have invented certain new and useful Improvements in Ice-Cream Freezers, of which the following is a specification.

This invention contemplates certain new and useful improvements in that type of ice cream freezer which is adapted to effect freezing of cream by a rocking motion, and the invention consists in certain constructions and arrangements of the parts hereinabove described and claimed, whereby a simple, cheap, durable, and efficient construction of freezer is produced.

For a full understanding of the invention and the merits thereof and also to acquire a knowledge of the details of construction of the means for effecting the result, reference is to be had to the following description and accompanying drawings, in which:

Figure 1 is a perspective view of my improved ice cream freezer; Fig. 2 is a transverse sectional view thereof; Fig. 3 is a detail perspective view of one of the freezing cans; Fig. 4 is a detail perspective and detached view of one of the latch bars and its locking plates; Fig. 5 is a detail perspective view on a reduced scale of the packing box that may be employed in connection with the freezer; Fig. 6 is a detail perspective view of the division block; and, Fig. 7 is a detail fragmentary view on an enlarged scale of one of the legs of the brace employed to hold the freezer as against its rocking movement.

Corresponding and like parts are referred to in the following description and indicated in all the views of the drawings by the same reference characters.

A box or receptacle 1 constituting the body of the freezer has its opposite sides extending downwardly to form rockers 2 that are preferably provided on their edges with corrugated rubber strips 3 adapted to render the device noiseless in its operation and to assist in preventing any creeping motion of the device along the floor or other support upon which the device is actuated. The interior walls of the box 1 as well as the lid 5, which is hinged, are provided with metallic linings that are preferably spaced somewhat from the wood-work of which the structure is composed so that the device may be

used, if desired, as an ordinary refrigerator or ice box. The lid 5 is rabbeted as shown so as to snugly fit within the box 1, and a packing strip 6 fits within the rabbeted portion so as to render the device air tight. The lid may be provided with any form of lock, such as the ordinary snap lock illustrated in the drawings.

The ends of the box are formed on their inner walls with opposing vertically extending recesses 8 in which the freezing cans 9 are adapted to be slipped so as to stand on end within the box in spaced relation to each other, with freezing material filling the spaces between them. The opposite sides of each can are preferably provided with spaced reinforcing strips 10 of galvanized iron or the like, and the cover 11 which is adapted to slip snugly over the box is provided at its upper side edges with similar strips 12, so that the top or cover may be readily lifted from the can after the freezing operation has been completed.

One or more plates 13 are secured to the inner face of one side of the box, and opposing plates 14 are secured to the opposite side, each plate 13 being formed with a recess and the opposing plates with a bayonet slot. Bars 15 are adapted to have one end slipped into a slot lying within the margin of the respective plates 13, the other ends of said bars being designed to be slipped downwardly into the bayonet slots of the plates 14 and adapted to be held therein by gravity or other forms of latches 16, so as to extend entirely across the series of freezing cans 9 and hold them securely in place during the rocking movement, as well as assisting in maintaining the lids or covers 11 of the respective cans.

While the box 1 may be rocked by any desired mechanical means, I have, in the present instance shown for this purpose, one or more end handles 17 and a side knob or handle 18 by which the freezer may be manually operated.

In the event that it is desired to utilize less than the full capacity of the freezer, I provide a division block 19 which is adapted to slip down into any pair of grooves or recesses 8 so as to divide the box into compartments. The division block 19 is provided with slots 30 adapted to accommodate the locking bars 15. After the cans have been filled and placed in the recesses 8 and locked

therein and packed around with a freezing mixture, the lid 5 is closed and the box rocked back and forth until the freezing operation has been completed. The freezer 5 cans 9 are then removed from the box and the frozen slabs are taken out and cut preferably into blocks. The blocks, as is customary, are wrapped in paraffin or similar paper and may be deposited in the covered 10 box 21 and replaced within the receptacle or body of the freezer and packed around with ice so as to be stored away until it is desired to use them.

1^a designates an orifice through which the 15 water may be drained off whenever desired.

To hold the box 1 firmly and prevent it from rocking, while it is being filled with or emptied of its contents, I provide a brace 22 consisting of two downwardly extending 20 legs 23 connected by a horizontal cross bar, as shown, and lying against the side of one of the rockers. Each leg 23 is formed with a vertically elongated slot 24 having an upwardly facing socket 25 and a downwardly 25 facing socket 26 formed in lateral branches of the said slot. The rocker is provided with two headed studs received in the respective slots 24 so that the operator by grasping the handle or finger piece 28 of the 30 cross bar of the brace, may move the same down and up so that the pins will lodge in the upwardly facing sockets 25 and hold the lower ends of the legs projected from the edge of the rocker into contact with the floor 35 or so that the said studs will lodge in the downwardly facing sockets 26 and thereby hold the brace in the retracted position.

From the foregoing description in connection with the accompanying drawings, it will 40 be seen that I have provided a very simple and efficient construction of ice cream freezer of the character herein set forth, which will be cheap to manufacture and durable, and which may be readily adjusted so as to be held firm against any rocking movement 45 while it is being filled or emptied and in which, also, the freezing cans may be slipped easily in place and as readily removed, said cans being securely held within the freezing 50 box by means of easily operated latch bars.

It will be noted that the recesses 8 are joined at their lower ends by horizontally extending depressions or channels adapted to receive the bottoms of the cans, so that 55 the cans will be supported firmly against any side pressure.

It is to be understood that my invention is applicable to churning as well as to the operation of making ice cream, as the same rocking motion, performed by the construction and 60 operation of parts herein disclosed will be

found exceedingly useful in the operation of transforming milk and cream into butter.

Having thus described the invention, what 65 is claimed as new is:

1. A freezer of the character described, consisting of a box provided with recesses for the reception of freezing cans, freezing cans adapted to be slipped down into the recesses, a plate secured to the inner face of one side 70 of the box and having an opening formed therein, another plate secured to the inner face of the opposite side of the box and formed with a bayonet slot, a locking bar, one end of which is adapted to be slipped 75 down into the bayonet slot, and a latch mounted upon the plate with the bayonet slot and adapted to extend over the adjacent end of the locking bar.

2. A freezer of the character described, 80 embodying a box and a lid therefor, the box being provided with rockers, and a brace adapted to hold said box as against a rocking movement, said brace including a pair of downwardly extending legs formed with slots 85 and oppositely facing notches, and a rocker of the box being provided with headed studs accommodated in said slots and adapted to rest in the respective notches thereof.

3. A freezer of the character described, 90 comprising a box and a lid, the box being formed with rockers, and a brace adapted to hold said box as against a rocking movement, said brace embodying two downwardly projecting legs and a cross bar connecting the 95 same, the legs being formed with vertical slots, and with upwardly and downwardly facing sockets communicating with said slots, and a rocker of the box being provided with headed studs accommodated in said slots and 100 adapted to lodge in the said sockets whereby to hold the brace projected from the lower edge of the rocker or in a retracted position with respect to said edge.

4. A freezer of the character described, 105 comprising a box formed with oppositely facing recesses in its inner wall, said recesses being adapted to receive freezing cans, and a division block adapted to be slipped down into any pair of recesses whereby to divide the 110 box into compartments, the said block being formed with a transverse slot and a locking bar adapted to extend through said slot and arranged for detachable engagement with opposite sides of the box, as and for the purpose set forth.

In testimony whereof I affix my signature in presence of two witnesses.

BENJAMIN G. BUTLER. [L. S.]
